UNITED STATES PATENT OFFICE.

NORMAN M. SMALL, OF WAYNESBORO, PENNSYLVANIA, ASSIGNOR TO FRICK COMPANY, OF WAYNESBORO, PENNSYLVANIA, A CORPORATION OF PENNSYLVANIA.

COMPRESSOR FOR GASES.

Application filed September 24, 1924. Serial No. 739,719.

To all whom it may concern:

Be it known that I, NORMAN M. SMALL, a citizen of the United States, residing at Waynesboro, in the county of Franklin and 5 State of Pennsylvania, have invented certain new and useful Improvements in Compressors for Gases, of which the following is a specification.

My said invention relates to compression 10 cylinders for ammonia or other gases, and the principal object thereof is to provide variable clearance pockets communicating with the cylinder for regulating the capacity of the compressor.

15 Referring to the accompanying drawings, which are made a part hereof and on which similar reference characters indicate similar parts:

Figure 1 is a vertical section on line 1—1 20 of Figure 2; and

Figure 2 is a vertical longitudinal section on line 2—2 of Figure 1.

In the drawings reference character 10 indicates the base of the compressor which 25 is provided with a cylinder 11 containing a piston 12 operated by any conventional or desired means through a connecting rod 13. The cylinder is provided with end closures 14, 15, and 16 of conventional or of any desirable character and has suction openings 17 and 18 and discharge openings 19 and 20, the suction and discharge openings being duplicated at the oposite ends of the cylinder as shown in Figure 2. The discharge 30 manifold is indicated at 21 and the discharge pipe is connected to a flange shown at 22.

A variable clearance pocket is provided at each end of the cylinder each of these pockets consisting of a secondary or subsidiary cylinder 23 opening into the main cylinder and closed at the outer end by a plate 24. The plate 24 has a central opening for a rod 25 having at its outer end a hand wheel 26 and at its inner end a piston plunger 27 fitting closely in the cylinder and tapered at its lower end to match the taper of the opening in the wall of the main cylinder so that the pocket may be practically closed and put out of use. The rod 25 is secured to the plunger 27 to move therewith and is provided at 28 with a threaded portion cooperating with threads in the longitudinal opening of the plate 24 for raising or lowering 55 the plunger.

This leaves a greater or less space underneath the plunger 27 to be filled with gas under pressure as the piston moves toward the clearance pocket in which the particular cylinder 27 is located. As the main piston retreats it follows that the compressed gas in the clearance pocket must expand until its pressure is below that of the suction gas before the suction valves will open and admit gas from the suction line. The gas in 60 the clearance pocket in expanding partly fills the main cylinder thus reducing the charge of fresh gas that can be drawn from the suction line and consequently reducing the capacity of the condenser, the action being, of course, similar at both ends of the same cylinder. While the capacity of the clearance pockets may be varied according to the needs of the case it is intended that the space shall be large enough to permit 65 a maximum reduction of approximately 50% in the capacity of the compressor.

I have shown and described a preferred embodiment of the invention but it will be obvious to those skilled in the art that 70 many changes can be made therein without departing from the spirit of the invention, therefore I do not limit myself to the specific embodiment shown in the drawings and described in the specification, but only as indicated in the appended claims.

Having thus fully described my said invention, what I claim as new and desire to secure by Letters Patent, is:

1. A compressor for gas comprising a cylinder, a piston, a cylindrical clearance pocket opening into the cylinder adjacent the end of the stroke of the piston, and a plunger in the cylindrical clearance pocket adjustable lengthwise thereof without stopping the compressor to vary the rate of operation of said compressor, substantially as set forth.

2. A compressor for gas comprising a cylinder, a piston, a cylindrical clearance pocket opening into the cylinder adjacent the end of the working stroke of the piston, a plate closing the outer end of the clearance pocket, a plunger in the pocket, and a rod carrying the plunger said rod extending out through said plate and having threaded engagement therewith whereby the rate of operation of the compressor may be varied substantially as set forth.

3. A compressor for gas comprising a cyl-

inder, a piston, a clearance pocket opening into the cylinder adjacent the end of the working stroke of the piston said pocket extending radially outward from the cylinder, 5 and a plunger adjustable longitudinally of the clearance pocket without interrupting the action of the compressor to provide a variable chamber underneath said plate for varying the rate of operation of the compressor, substantially as set forth.

10 4. In a gas compressor, a cylinder, a piston, a branch cylinder extending from the main cylinder, a tapered passage leading

through the cylinder wall from said branch cylinder, and a plunger adjustable lengthwise of the branch cylinder to provide a variable clearance pocket for varying the rate of operation of the compressor said plunger having a tapered extension adapted to close said tapered passage, substantially 15 as set forth.

In witness whereof, I have hereunto set my hand at Waynesboro, Pennsylvania this 23rd day of September, A. D. nineteen hundred and twenty-four.

NORMAN M. SMALL.
